(57) **CLAIM**

The ornamental design of a recessed can light fixture, as shown and described.

DESCRIPTION

FIG. 1 is a side perspective view of a first embodiment of a recessed can light fixture embodying my new design;

FIG. 2 is a rear perspective view thereof;

FIG. 3 is a front elevational view thereof;

FIG. 4 is a rear elevational view thereof;

FIG. 5 is a left side elevational view thereof, the right side elevational view being a mirror image thereof;

FIG. 6 is a side perspective view of a second embodiment of a recessed can light fixture embodying my new design;

FIG. 7 is a rear perspective view thereof;

FIG. 8 is a front elevational view thereof;

FIG. 9 is a rear elevational view thereof; and,

FIG. 10 is a left side elevational view thereof, the right side elevational view being a mirror image thereof.

The structural subject matter shown in broken lines forms no part of the claimed design.
